UNITED STATES PATENT OFFICE

2,372,785

OIL WELL PUMP

Peter W. Jenson, Chelsea, Okla.

Application January 25, 1944, Serial No. 519,663

3 Claims. (Cl. 103—179)

This invention relates to pumps especially designed for use in connection with oil wells, and the primary object of the invention is to provide a novel form of oil well pump having simple and efficient means to trap sediment and scale that may be pumped up with the oil, thereby preventing the sediment and scale from passing back into the working cylinder or barrel of the pump and causing damage or undue wear of the working valve or working barrel.

A more specific object of the invention is to provide a pump of the above character wherein the oil is caused to flow in a downward path after leaving the working barrel so as to cause effective gravitation of the sediment and scale into the collection chamber and positively prevent its return to the working barrel.

A further object of the invention is to so construct the pump that the capacity of the sediment and scale-trapping chamber may be readily increased if desired.

Still another object of the present invention is to provide a pump of the above character wherein provision is made for effectively sustaining the working barrel centrally of the trap or collection chamber and coaxial with the inlet pipe for the working barrel and the well tubing.

Other objects and features of the present invention will become apparent from the following description when considered in connection with the accompanying drawings, and the invention consists in the novel form, combination and arrangement of parts hereinafter more fully described, shown in the drawings and claimed.

In the drawings, wherein like reference characters indicate corresponding parts throughout the several views:

Figure 1 is an elevational view of an oil well pump constructed in accordance with the present invention.

Figure 2 is a similar view with the casing of the trap chamber and adjacent parts broken away and in vertical section to reveal internal details, the plane of section being substantially that indicated by the line 2—2 in Figure 1.

Figure 3 is a central vertical section taken on line 3—3 of Figure 2.

Figure 4 is an enlarged fragmentary vertical section taken on the plane of line 4—4 of Figure 3, parts being omitted and parts being broken away.

Figure 5 is a horizontal section taken on line 5—5 of Figure 4.

Figure 6 is a horizontal section taken on line 6—6 of Figure 3.

Figure 7 is a horizontal section taken on line 7—7 of Figure 3.

Referring in detail to the drawings, the present pump includes a tubular casing 5 of greater diameter than and coupled at its upper and lower ends to the lower end of the wall tubing 6 and the upper end of an inlet or anchor pipe 7 by means of reducer fittings 8 and 9, respectively. Positioned axially of and within the casing 5 is a working barrel including a main relatively long upper section 10 and a supplemental relatively short lower section 11 coupled together by a threaded coupling sleeve 12, the lower section 11 being threaded into the lower end portion of the reducer fitting 9. The upper end of the working barrel is sustained in spaced concentric relation to the casing 5 by means of a spider including a collar 13 having radial spaced lugs 14 engaging the inner surface of the casing 5. The detachable threaded connections provided between the fittings 8 and 9 and the parts connected thereby permit ready assembly or disassembly of the parts. It will be apparent that by substituting a longer casing 5 for that shown and a correspondingly longer barrel section 11, the capacity of the chamber between the casing 5 and the barrel 10, 11 may be increased if desired.

Tightly fitted within the upper end of the working barrel is a centrally apertured plug generally indicated at 15 and including split normally expanded elements 16 carried by a nipple 17 and capable of contracting when the plug is forced into the upper end of the working barrel. This provides a snug frictional fit of the plug within the barrel so that it will remain in position at the upper end of the latter. The nipple projects above the collar 13 and has a short pipe section 18 threaded therein. Also, the usual sucker rod 19 extends downwardly through the pipe section 18 into the working barrel where it is equipped with the usual working valve or valved piston 20. The sucker rod and tubing of course extend to the top of the well in the usual manner, and fitted and secured on the sucker rod, as by welding at 21, is a cylinder 22 having a closed upper end but open at the bottom end thereof. This cylinder 22 surrounds the pipe section 18 in spaced concentric relation to the latter, and the arrangement is such that the oil pumped upwardly from the working barrel will be discharged from the upper end of the pipe section 18 into the cylinder 22, and the latter will direct the oil downwardly outside the pipe section 18 for being discharged from the lower end of cylinder 22 above the plug 15. This downward flow of the

oil before again passing upwardly into and through the tubing 6 assists gravitation of sediment and scale from the oil downwardly into the trap chamber 23 provided between the casing 5 and the working barrel. Thus, the sediment and scale will be prevented from returning to the working barrel for damaging or causing undue wear of the latter or the working valve 28. In operation, it will of course be understood that the cylinder 22 moves up and down with the sucker rod 13 and relative to the pipe section 18, the latter acting as a discharge pipe for the upper end of the working barrel. The top of the spider collar 13 is preferably beveled inwardly and downwardly, as at 24, so as to facilitate entry of the plug 45 into the working barrel when assembled therein. A conventional standing valve 28 is fitted in the lower end of the upper section 18 of the working barrel below the working valve or piston 26.

In operation, the oil is pumped in a well known manner by reciprocation of the working valve or piston 26 by actuation of sucker rod 13, the oil being drawn through the standing valve and forced upwardly through the working valve and being subsequently lifted by the latter and forced upwardly through the discharge pipe 18. The oil is then caused to flow outwardly and downwardly between the pipe 18 and cylinder 22, sediment and scale being deposited in the trap chamber 23, as mentioned above, and the oil ultimately passing upwardly into and through the tubing 6 to the surface of the well. It will be seen that the construction provides for efficient operation in the intended manner, as well as a compact and durable arrangement of parts affording a simple and efficient device. In handling the pump, the working barrel is effectively sustained in proper position and prevented from lateral distortion by means of the spider 13, 14. Minor changes in the details of construction illustrated and described are contemplated, such as fairly fall within the spirit and scope of the invention as claimed.

What I claim as new is:

1. In a pump, an outer casing, a working barrel within the outer casing, a working valve operating within the working barrel, a centrally apertured plug removably fitted in the upper end of the working barrel and provided with a central upwardly projecting discharge pipe, a sucker rod extending through the discharge pipe and plug and connecting to the working valve for operating the latter, a cylinder carried by the sucker rod and disposed over the discharge pipe, said last-named cylinder being closed at its upper end so as to direct the oil downwardly about the discharge pipe as it is discharged from the latter, whereby to facilitate gravitation of sediment and

scale from the oil into the space between the casing and the working barrel, and a spider including a collar removably secured on and projecting above the upper end of the working barrel and having radially projecting lugs contacting the casing to maintain the upper end of the working barrel centered with respect to said casing, the top of said collar being beveled inwardly and downwardly to facilitate entry of the plug into the working barrel.

2. In a pump, an outer casing, a working barrel within and spaced from the outer casing, a working valve operating within the working barrel, a centrally apertured plug in the upper end of the working barrel and provided with a central upwardly projecting discharge pipe, a sucker rod extending through the discharge pipe and plug and connecting to the working valve for operating the latter, a cylinder carried by the sucker rod and disposed over the discharge pipe, said last-named cylinder being closed at its upper end so as to direct the oil downwardly about the discharge pipe as it is discharged from the latter, whereby to facilitate gravitation of sediment and scale from the oil into the space between the casing and the working barrel, and an inlet pipe smaller than and coupled to the lower end of the casing, said working barrel including an elongated main upper section and a relatively shorter lower section detachably coupled to said upper section, said lower section being removably connected at its lower end with the inlet pipe and casing.

3. In a pump, an outer casing, a working barrel within the outer casing, a working valve operating within the working barrel, a centrally apertured plug in the upper end of the working barrel and provided with a central upwardly projecting discharge pipe, a sucker rod extending through the discharge pipe and plug and connecting to the working valve for operating the latter, a cylinder carried by the sucker rod and disposed over the discharge pipe, said last-named cylinder being closed at its upper end so as to direct the oil downwardly about the discharge pipe as it is discharged from the latter, whereby to facilitate gravitation of sediment and scale from the oil into the space between the casing and the working barrel, said plug comprising a nipple connected to the lower end of the discharge pipe and split normally expanded members mounted on the intermediate portion of the nipple and frictionally engaged with the inner surface of the working barrel, the lower end of said discharge pipe being threaded in the upper end of said nipple.

PETER W. JENSON.
